UNITED STATES PATENT OFFICE.

OSCAR F. HALVERSON, OF JANEVILLE, WISCONSIN.

LEAF-TURNER.

No. 833,828.

Specification of Letters Patent.

Patented Oct. 16, 1906.

Application filed February 24, 1906. Serial No. 302,712.

To all whom it may concern:

Be it known that I, OSCAR F. HALVERSON, a resident of Janesville, in the county of Rock and State of Wisconsin, have invented 5 certain new and useful Improvements in Leaf-Turners; and I do hereby declare the following to be a full, clear, and exact description of the invention, such as will enable others skilled in the art to which it appertains 10 to make and use the same.

My invention relates to improvements in leaf-turners, the object of the invention being to provide improved mechanism for moving a magnet to turn the leaves; and the invention consists in certain novel features of construction and combinations and arrangements of parts as will be more fully herein-after described, and pointed out in the claims.

In the accompanying drawings, Figure 1 20 is a view in elevation, illustrating my improvements. Fig. 2 is a view in section. Fig. 3 is a sectional view illustrating the attachment of the clamp 9. Fig. 4 is a detail view showing the attachment of the magnet 25 to the rod 14. Fig. 5 is an enlarged rear view, partly broken away, showing the music-support and devices for operating the arm or rod 14. Fig. 6 is a detail view showing the shaft 13, spool 20, and rod 14.

1 represents my improved music-holder, which is preferably mounted on a telescoping rod 2, supported by a folding tripod 3.

The music holder or rack 1 may be made in a great many ways; but I prefer to employ 35 one of the folding type which permits it to be folded into small space for transportation.

To the back of the center bar of the music rack or holder 1 a plate 4 is clamped by bands 5, pivotally secured to the plate at one end, 40 extending over the face of the center bar and securely clamped by screws 6 and thumb-nuts 7, as clearly shown, and an upwardly-projecting rod 8 is secured adjustably to the center bar by clamps 9. This bar has a cord 10, 45 secured in openings in its upper end and is adapted to be passed down the fold of the music and secured to the plate 4 to hold the music in proper position on the rack.

Below the music-supporting bar 11 of the 50 rack the plate 4 is made with an ear 12 stamped therefrom and having an opening alining with a similar opening in an ear 12^a at the lower end of plate 4 to receive a short shaft 13, on which a spool 20 is secured, and a 55 rod 14, located at right angles to shaft 13, is

secured thereto or made integral therewith. This rod 14 is flattened or made angular to enter an angular opening in a bracket 15, adjustably secured on the rod by a thumb-screw 16, and this bracket 15 supports a 60 magnet 17 to attract metal disks or plates 18 on the music leaves or sheets and turn the leaves, as will be hereinafter explained.

An eyebolt 19 is passed through spool 20 and shaft 13, rigidly securing them together, 65 and a cord 21 is secured to the bolt 19, passed around spool 20, thence through the opening in plate 4 over a pulley 22, and down to a treadle 23. The treadle 23 is made approximately A shape, with its longitudinal bars 70 pivotally secured together and connected by a cross-bar pivotally secured at one end and removably secured at its other end to permit the treadle to be folded for shipment, and the free ends of the longitudinal bars are bent 75 and sharpened, forming teeth 25 to engage in the carpet and prevent movement of the treadle out of positon beneath the operator's foot. Pulley 22 is supported at the end of a wire or other spring 26, secured to plate 4 by 80 a thumb-nut 28, and has one or more coils between its ends to give to the spring the necessary tension. The free end of the spring 26 is connected by a cord 29 with the bolt 19 in spool 20, so that when the spool is turned 85 by cord 21 to turn a leaf the cord 29 will be wound on the spool and draw the spring 26 downward, and when pressure is released from the treadle the spring will draw the cord 29 outward, turn spool 20, and return 90 the parts to their normal positions.

To the right-hand lower corner of the music-holder or rack 1 a plate 30 is clamped, as shown, to rest back of the corner of the leaves and receive the shock of the returning 95 magnet and hold the leaves in position to be engaged by the magnet.

I do not confine myself to any particular manner of fastening the metal plates or disks 18 to the leaves, as this may be done in 100 a great many ways, and the thin plates or disks used for the purpose will not disfigure the music nor detract in anyway therefrom.

It will be observed that shaft 13 and spool 20 are located slightly to the left of the center 105 of the music rack or holder, which compels the magnet to move in an arc of a circle different from the metal disks or plates 18, and hence the magnet as it nears the left of the rack after it has thrown or turned the leaf 110.

will draw away from the disk or plate and be ready to return to its former position without the leaf it has turned.

The operation of my improvements is as follows: The normal position of the magnet is on the right-hand side of the rack or holder against the metal disk on the music-leaf. When pressure is applied on treadle 23, the cord 21 will be drawn down to turn spool 20, and thus swing the rod 14 and magnet 17, and the engagement of the magnet with the metal disk 18 will cause the leaf to follow the magnet until the latter reaches a point near its extreme throw, when the difference in the arcs through which the magnet and leaf move will cause the magnet to slide off the metal disk and release itself therefrom. This turning movement of spool 20 winds cord 29 thereon to pull down spring 26, and when pressure on the treadle is released spring 26 will pull cord 29 to turn spool 20 in the reverse direction and return rod 14 and magnet 17 to their former and normal positions to engage the metal disk on the next leaf to be turned. The operator is thereby enabled to turn the leaves by pressure of his foot on treadle 23, and his hands are free for use with the musical instrument he is playing.

30 A great many slight changes might be made in the general form and arrangement of the parts described without departing from my invention, and hence I do not re-

strict myself to the precise details set forth, but consider myself at liberty to make such slight changes and alterations as fairly fall within the spirit and scope of my invention.

Having fully described my invention, what I claim as new, and desire to secure by Letters Patent, is—

1. In a leaf-turner, the combination with a leaf-support, of a spool, a rod secured to the spool, a magnet on the rod, a spring, a pulley carried by said spring, a treadle, a cord secured to the spool, wound thereon, passed over the pulley carried by the spring and secured to the treadle, and a cord connecting the spring and spool.

2. In a leaf-turner, the combination with a leaf-support and metal pieces to be attached to the leaves to be turned, of a spool located to the left of the center of said support, a rod secured to the spool, a magnet secured to the rod and adapted to engage the metal pieces on the leaves, a spring, a pulley thereon, a cord connecting the spring and spool, a treadle, and a cord connecting the spool and treadle and passed over the pulley.

In testimony whereof I have signed this specification in the presence of two subscribing witnesses.

OSCAR F. HALVERSON.
